UNITED STATES PATENT OFFICE.

JAMES J. BOYLE, OF NEW YORK, N. Y., ASSIGNOR OF ONE-HALF TO DANIEL P. BOYLE,
OF NEW YORK, N. Y.

PENHOLDER.

Application filed April 13, 1923. Serial No. 631,786.

To all whom it may concern:

Be it known that I, JAMES J. BOYLE, a citizen of the United States, and a resident of the borough and county of Bronx, in the city and State of New York, have invented a new and useful Penholder, of which the following is a specification.

This invention relates to ejecting penholders, and the object is to provide means for holding the movable ejecting member snugly in position irrespective of friction and for restoring it automatically to normal position after it has been operated to eject the pen.

In the accompanying drawings, forming a part hereof:

Fig. 1 is a perspective view of a penholder embodying the invention, portions of the grip and grip tube being broken away, and a pen being indicated in broken lines;

Fig. 2 is an enlarged view of the forward part of the penholder, the grip being shown in longitudinal section and the other parts in elevation;

Fig. 3 is a similar view showing the grip tube also in section, and portions of the filler broken away and in section, a pen being shown in full lines;

Fig. 4 is a view like Fig. 3 showing the grip and grip tube slid forward to eject the pen, the spring being thereby compressed; and

Fig. 5 is a cross-section on the line 5—5 of Fig. 3.

The penholder illustrated has a shaft 1, a filler or head 2, and a reduced stem 3 connecting the filler with the shaft, there being a shoulder 4 at the back of the filler where it joins the stem, and another shoulder 5 between the stem and the forward end of the shaft. These parts may be in one piece or otherwise as desired. Enclosing the filler and stem is a grip tube 6, preferably carrying a grip 7 of rubber or other material, re-

tained at the front end by an out-turned flange 8. As in my prior Patent 1,371,292, dated March 15, 1921, the grip tube is preferably provided with a plurality of ejector indentations 9, which operate in longitudinal grooves 10 in the filler.

The rear end of the grip tube is formed with an inturned flange 11, and between the tube and the stem 3 there is a spring chamber 12. In this chamber, coiled about the stem, is a spring 13, normally under some compression between the flange 11 and the forward shoulder 4, which serve as spring abutments.

In order to eject or remove the pen, the grip tube must be pushed forward against the resistance of this spring, increasing its compression, as will be seen in Fig. 4, and when the grip is then released the spring returns the grip tube to its normal position and holds it tight against the shoulder 5. In the operation of pushing forward on the grip 7, the flange 8 keeps it from slipping off the grip tube. Because of the action of the spring no retaining flange for the grip is required at the rear end of the tube.

While I have thus described the preferred embodiment of the invention, I wish it to be understood that I do not limit myself to the precise construction.

What I claim as new is:

A penholder having a shaft, a filler and a reduced stem connecting the filler and shaft, a slideable ejecting grip tube normally enclosing the filler and stem and having an internal flange on its rear portion, there being a spring chamber between the tube and the stem, and a spring in said chamber acting between said flange and the shoulder at the back of the filler to urge the grip tube rearward against the shaft.

JAMES J. BOYLE.
